UNITED STATES PATENT OFFICE.

FISHER H. LIPPINCOTT, OF PHILADELPHIA, PENNSYLVANIA, ASSIGNOR TO THE VICTOR SLICING MACHINE CO., A CORPORATION OF DELAWARE.

TABLE-FEEDING MECHANISM FOR SLICING MACHINES.

Application filed July 27, 1921. Serial No. 487,867.

To all whom it may concern:

Be it known that I, FISHER H. LIPPINCOTT, a citizen of the United States, residing at Philadelphia, county of Philadelphia, State 5 of Pennsylvania, have invented a new and useful Table-Feeding Mechanism for Slicing Machines, of which the following is a specification.

My invention relates to a slicing machine 10 of the type in which the table bed is reciprocated with respect to a rotating cutter and in which provision is made for effecting the advance of the table towards the cutter in accordance with the thickness of slice de- 15 sired.

My invention comprehends a novel construction and arrangement of table feeding mechanism whereby the table is advanced step by step during its reciprocation, and 20 wherein when the table reaches the limit of its forward travel the feed nut connected with the table becomes disengaged from its feed screw, the reengagement of the feed screw with the feed nut being manually ac- 25 complished by a longitudinal movement of the feed screw.

It further comprehends a novel construction of a feed nut and a novel manner of detachably connecting it with the article 30 carrying table.

It further comprehends a novel construction and arrangement of a ratchet mechanism which is rendered inoperative when the feed screw is rotated in a reverse direction, thereby enabling one to effect a quick 35 return of the article carrying table.

It further comprehends novel mechanism for regulating the ratchet feed and thereby the thickness of the cut.

Other novel features of construction and advantage will hereinafter more fully appear in the detailed description of the invention.

For the purpose of illustrating my invention, I have shown in the accompanying drawings a typical embodiment thereof which is at present preferred by me, since this embodiment will be found in practice to give satisfactory and reliable results. It is, 45 however, to be understood that the various instrumentalities of which my invention consists can be variously arranged and organized and that my invention is not limited to the precise arrangement and organiza-

tion of these instrumentalities as herein 55 shown and described.

Figure 1 represents a top plan view of a slicing machine in which is employed a table feeding mechanism embodying my invention. 60

Figure 2 represents a section on line 2—2 of Figure 1.

Figure 3 represents a section, on an enlarged scale, taken on the same section line as Figure 2 but showing certain of the parts 65 in a different relation from that seen in Figure 2.

Figure 4 represents, in sectional elevation and in detached position, the feed nut seen in Figures 2 and 3. 70

Figure 5 represents a section on line 5—5 of Figure 1.

Figure 6 represents a section on line 6—6 of Figure 2.

Figure 7 represents a section on line 7—7 75 of Figure 5.

Figure 8 represents a bottom plan view of the pawl arrangement seen in Figure 7.

Similar numerals of reference indicate corresponding parts. 80

Referring to the drawings.

1 designates the framework of the machine which is provided with the guides 2 on which travel the rollers 3 carried by the bed 4. In order to effect the reciprocations 85 of the bed 4, the framework 1 has journalled therein a main driving shaft 5 to which is connected a fly-wheel 6 provided with a handle 7 whereby it may be manually rotated, it being of course apparent that the shaft 5 90 may be motor driven if desired. The shaft 5 is provided with a gear 8 which meshes with a gear 9 mounted on a shaft 10 suitably journalled in the framework of the machine. The shaft 10 has connected to it the crank 95 arm 11 to which is connected one end of a connecting rod 12, the other end of which is pivotally connected at 13 to the bed 4. The shaft 10 is provided with a gear 14 which meshes with a gear 15 mounted on a shaft 16 100 which latter is operatively connected by means of a sprocket wheel and chain arrangement 17 with the shaft of a cutter 18 suitably mounted on the framework of the machine. This cutter is in the form of a 105 circular cutter having its cutting plane presenting at an angle to the plane of the cut. The reciprocating bed 4 has slidably mount-

ed upon it an article receiving table 19 which at its forward end is provided with any desired type of meat clamping mechanism 20.

The bed 4 has journalled in it a rotatable feed screw 21 which is provided with the cylindrical bearing portion 22 which carries a set collar 23 in order to limit the rearward or outward movement of the feed screw, and, at its inner end, it is provided with a reduced portion 24 which forms a shoulder 25. In proximity to this shoulder 25 is a smooth bearing portion 26, and at the opposite end of the threads 27 is a smooth bearing portion 28 which forms with the bearing portion 22 a shoulder 29. The bearing portion 26 has loosely mounted on it a collar 30. 31 designates the feed nut which is provided with the smooth unthreaded bore 32, and at one end with the threads 33 which open 20 into said bore.

The feed nut 31 is provided with an upwardly extending lug 34 having a slot 35 in its front wall. The feed nut is guided in a longitudinally extending slot 36 in the upper 25 table or wall of the bed 4 and extends into an aperture 37 in the bottom of the article carrying table 19, and is secured in locked position in such aperture 37 by means of a lever 38 pivoted at 39 to the bottom of the article carrying table 19, one end of the lever 38 being adapted to enter the slot 35 in order to effect the locking engagement between the feed nut and the article carrying table, while the opposite end of said lever 38 extends 35 exteriorly of the article carrying table and is upwardly and laterally deflected to form a grasping handle 40 by means of which it may be readily manipulated when desired. The feed screw 21 at its outer end is provided with the reduced neck 41 on which is keyed a ratchet 42 and on which is loosely mounted a pinion 43, said pinion and ratchet being retained in proper position by means of a shoulder 44, and the hub of the handle 45 is secured on the extension 41 by means of a pin 46.

The pinion 43 has mounted on it a pawl 47 which is preferably made of a piece of spring metal which is received in the slots 50 48 of the pins 49 which extend outwardly from the pinion 43. The bed 4 in proximity to the pinion 43 is provided with the outwardly extending post 50 which passes beneath the pawl 47, so that the latter overhangs such post 50, which latter serves as a pawl releasing member as will hereinafter be fully explained.

51 designates a bracket which serves as a guard to cover the pinion 43 and the ratchet 42, and this guard is secured to a fixed portion of the bed by means of a fastening device 52. The lower portion of the bracket 51 is apertured to form bearings 53 for a rack bar 54 which is freely slidable therein and meshes with the pinion 43. The rack

bar 54 preferably has its ends of reduced diameter, as will be understood by reference to Figure 5, and one end is adapted to contact with a stop 55 which is adjustably carried by one of the brackets 56 extending from the framework of the machine. The stop 55 is in the form of a bolt in threaded engagement with a bracket 56 and secured in its adjusted position by means of a nut 57. The brackets 56 have connected to them in any desired manner the spaced bars 58, each of which is provided near one end with the rack teeth 59 with which are adapted to engage the pawl members carried by a block 60 which is secured to a plunger 61 so slidable through a slide 62, positioned between the space bars 58 and having the overhanging flanges 63 which ride on the top of said bars. The slide 62 is recessed, as at 64, in order to receive a spring 65, one end of which abuts against the lower wall of the recess 64, while its opposite end abuts against a shoulder on the plunger 61, so that the stop member formed by this construction will be retained in the position to which it is adjusted.

The slide 62, see Figure 1, is provided with a pointer 66 which travels over a graduated plate 67, the graduations being indicative of the thickness of a slice which is to 95 be cut. The plate 67 is preferably in the form of an angle secured to the outer bar 58 in any desired manner, see Figure 2.

The operation of my novel table feeding mechanism will now be readily apparent to 100 those skilled in this art, and is as follows:—

The meat is clamped on the article carrying table 19 by means of the clamping mechanism 20 which may be of any desired or conventional type. The operator actuates 105 the handle 45 in a lefthand direction to feed the table into proximity to the cutter 18. The operator then rotates the main driving shaft 5 by means of the handle 7, and, due to the operative connection between the 110 driving shaft 5 and the bed or reciprocating carriage, such carriage is reciprocated during the rotation of the cutter 18, together with the article carrying table 19 which is supported on such carriage.

As the reciprocating carriage 4 reaches the end portion of the travel of its rearward movement, the rack 54 contacts with the slide 62 of the adjustable stop mechanism; and, as the carriage 4 continues to move 120 rearwardly, the pinion 43 will be partially rotated, thereby causing the pawl 50 to advance the ratchet 42 and thereby effect a partial rotation of the feed screw 21 to which the ratchet 42 is keyed. This rotation of the feed screw effects the advancement of the feed nut 31 and thereby of the article carrying table 19 to which it is connected. On the forward movement of the reciprocating carriage 4 the rack will engage the adjust- 130

able stop 55 and be returned to its initial or starting position. It will thus be understood that during the reciprocations of the carriage 4 the article carrying table 19 is advanced step by step towards the cutter 18.

As soon as the article carrying table 19 reaches the limit of its forward travel the feed nut 31 feeds off the threads 27 and the feed screw 21 becomes disengaged from such threads, so that the rotation of the feed screw is ineffective to further advance the table 19. With the parts in this position it will be seen that if the operator rotates the handle 45 in a clockwise direction no movement will be imparted to the article carrying table 19 unless the handle is pushed forwardly to bodily move the feed screw forwardly so that the threads 27 will engage with the threads 33 in the feed nut. When the feed screw 21 is moved bodily forwardly to engage the threads of the feed screw with the feed nut, then a quick return of the article carrying table to its initial or starting position will be effected, it being seen that the spring pawl 47 will ride up on the stop pin 50 and become disengaged from the ratchet 42.

The article carrying table 19 can be fed rapidly in its forward direction by rotating the handle 45 in a counter clockwise direction, during which movement, the pawl 47 will ride over the teeth of the ratchet 42. The thickness of the cut is regulated by the adjustable stop mechanism carried by the bars 58. It will be seen that when the plunger 61 is pressed downwardly the pawl carrying member 60 will be disengaged from the teeth 59 so that the slide 62 can be adjusted to any desired position, and when the operator releases the pressure from the plunger 61 the spring 65 will cause the plunger to move upwardly so that the slide 62 will be fixed in its adjusted position.

It will thus be apparent that the operator can, at any time, effect the quick advance or a quick return of the article carrying table 19.

It is desirable in a machine of this character, in order to maintain it in a sanitary condition, to have the article carrying table 19 removable so that the upper table of the reciprocating carriage can be cleaned. This can be readily accomplished in my machine by actuating the handle 40 of the lever 38 in order to move it out of the slot 35 in the feed nut 31, whereupon the article carrying table 19 can be readily removed, as is apparent.

Having thus described my invention, what I claim as new and desire to secure by Letters Patent, is:

1. The combination with a rotatable threaded member, of a co-operating member moved thereby and arranged to become operatively disengaged from said threaded

member when it reaches the end of its forward travel, and to become operatively re-engaged with said threaded member when the threaded member is bodily moved longitudinally and its direction of rotation reversed. 70

2. The combination with a feed screw, of a feed nut moved thereby and adapted to be automatically disconnected from said feed screw when it reaches the limit of its forward travel, and to remain disconnected until the feed screw is bodily advanced longitudinally and its direction of rotation reversed. 75

3. In a slicing machine, a reciprocating carriage, an article receiving table slideable on said carriage, a feed nut relatively movable with respect to said carriage and having a slot opening through a wall thereof, means carried by said table to enter said slot and lock said table with respect to said feed nut, and means to actuate said feed nut to effect the desired movement of said article receiving table. 80 85

4. In a slicing machine, a reciprocating carriage, a feed nut guided in said carriage, an article receiving table slideable on said carriage and having an aperture to receive said feed nut, said feed nut having a slot therein, and a lever carried by said table, having one end adapted to enter said slot to lock the feed nut and table together, and having its opposite end extending accessible to the operator to form a grasping handle. 90 95

5. In a slicing machine, a reciprocating carriage, a table slideable on said carriage and forming a support for the article to be sliced, a feed nut guided in said carriage and operatively connected with said table to move it, a feed screw having intermediate 100 its ends a threaded portion co-operating with said feed nut to move it, said feed nut co-operating with said feed screw to become disengaged from said threaded portion when the table reaches the limit of its forward travel and to remain disengaged from said threaded portion when in such position on a rotation of the feed screw in one direction or the other, said feed screw being mounted in said carriage to have limited 110 longitudinal movement, whereby after becoming disengaged from said threaded portion and advanced longitudinally it will become reengaged on longitudinal movement of the feed screw and carry the feed nut and 120 table rearwardly on a reverse rotation of the feed screw, and means to effect the intermittent feed of said feed screw during the reciprocations of said carriage. 115 120

6. In a slicing machine, a reciprocating carriage, a feed screw mounted therein to have limited longitudinal movement, a feed nut having a bore to receive said feed screw and having a portion only of the bore threaded, a grasping handle for actuating 130

- said feed screw, a pinion on said feed screw, an intermittently actuated rack to operate said pinion, a pawl carried by said pinion, a ratchet fixed to said feed screw and with 5 which said pawl co-operates to effect the feed of the feed screw, and means to automatically release said pawl when said feed screw is rotated in a direction to move the feed nut rearwardly.
10. 7. In a slicing machine, a reciprocatory carriage, a feed screw mounted therein to have limited longitudinal movement and having a threaded portion intermediate its ends, a feed nut driven by said feed screw, a 15 ratchet fixed to said feed screw, a pinion loose on said feed screw, a pawl carried by said pinion and co-operating with said ratchet, a stop on said carriage to render said pawl inoperative when the feed screw 20 is rotated in a reverse direction, and said feed nut being disengaged from said threaded portion when it reaches the limit of its forward travel and being adapted to reengage with said threaded portion on a bodily 25 longitudinal movement of said feed screw.
8. In a slicing machine, a reciprocatory carriage, a feed screw mounted therein to have limited longitudinal movement and having a threaded portion terminating in an 30 unthreaded portion, a feed nut engaging said threaded portion and adapted to be disconnected therefrom when it reaches the limit of its forward travel and to remain disconnected until the feed screw is moved 35 longitudinally, a ratchet on said feed screw, a pinion loose on said feed screw, a pawl carried by said pinion to engage said ratchet, a rack to actuate said pinion, and stop members to effect the operation of said 40 rack during the reciprocation of said carriage.
9. In a slicing machine, a reciprocatory carriage, a feed screw mounted therein to have limited longitudinal movement, a feed 45 nut co-operating with said feed screw and adapted to be disengaged therefrom when it reaches the limit of its forward travel and to remain disengaged until the feed screw is bodily advanced longitudinally and its direction of rotation reversed, a ratchet fixed 50 to said feed screw, a pinion loose on said feed screw, a pawl carried by said pinion to co-operate with said ratchet, a manually actuated handle for said feed screw, a rack carried by said carriage and meshing with 55 said pinion, means to intermittently actuate said rack during the reciprocations of said carriage, and means to effect the release of said pawl when said handle is actuated in a direction to effect the rearward movement of 60 the feed nut, whereby a quick return of the feed nut is effected.
10. In a slicing machine, a reciprocatory carriage, an article carrying table slidable on said carriage, and means to feed said 65 table during the reciprocations of said carriage including the following instrumentalities, a feed screw, a rack and pinion arrangement to actuate the feed screw, stationary members having teeth therein, a stop slidable on said members and in the path of said rack and including a manually releasable spring pressed member longitudinally slidable with said stop along said members and adapted to engage said teeth and retain said 70 stop in adjusted position indicative of the thickness of the slice which is to be cut.
11. In a slicing machine, a reciprocatory carriage, an article carrying table slidable on said carriage, and means to feed said 80 table during the reciprocations of said carriage including the following instrumentalities, a feed screw, a rack and pinion arrangement to actuate the feed screw, a stop support, a stop adjustably mounted to be slid 85 along said support in the path of the rack and having a pointer, and a graduated plate having graduations co-operating with said pointer to indicate the thickness of the slice which is cut, said stop including a spring actuated locking member carried by it and longitudinally adjustable with it along said stop support, said spring causing said stop to be interlocked with said support, said locking member being adapted to be manually actuated.
